UNITED STATES PATENT OFFICE.

CHARLES J. GETERMAN, OF CANTON, OHIO, ASSIGNOR TO JOHN E. McLAIN, OF CANTON, OHIO.

HEADLIGHT.

1,130,391.

Specification of Letters Patent.

Patented Mar. 2, 1915.

Application filed March 21, 1908. Serial No. 422,449.

To all whom it may concern:

Be it known that I, CHARLES J. GETERMAN, a citizen of the United States, residing at Canton, in the county of Stark and 5 State of Ohio, have invented certain new and useful Improvements in Headlights; and I do hereby declare that the following is a full, clear, and exact description of the same, reference being had to the accompanying drawing, making a part of this specification.

This invention relates to electric headlights.

One object of the invention is to securely 15 hold the base, carrying the lamp mechanism and reflector, in position with relation to the exterior casing and at the same time permit the ready removal of the lamp mechanism from the casing for purposes of inspection or repair.

Heretofore it has been common to mount the reflector and lamp mechanism upon a base extending longitudinally of the casing at one side thereof, said base being adapted 25 to slide upon guides into and out of the casing, detachable fastenings securing the base in position upon the guides. With such constructions, if the detachable fastenings should become disengaged, the acceleration 30 and retardation of the car or locomotive might cause the base and the mechanism thereon to slide back and forth in the casing with liability of damage to the parts. Moreover, if parallelism of the base and guides 35 is not maintained in sliding the mechanism in and out, the parts will bind and may become bent or broken. According to the present invention, the base and the mechanism thereon are securely held against sliding 40 at any time, the base being lifted and turned easily on a hinge or pivot when it is desired to remove the lamp mechanism from or replace it in the casing. When the mechanism is in position within the casing gravity tends to secure it in that position.

Another object of the invention is to simplify the construction and increase the reflecting surface of the reflector.

Heretofore, where an arc was formed 50 within or between the front edge and the

center of a parabolic or other concave reflector between two carbons inclined to the focal axis of the reflector, two holes have been cut in the reflector, one for each of the carbons or the regulating means therefor, or 55 both. According to the present invention a single hole for one of the carbons only is employed.

Another object of my invention is to arrange and support the electromagnet for 60 controlling the arc in front of the focus of the reflector, and in such manner as not to impede the rays of reflected light.

Another object of the invention is to provide improved and greatly simplified means 65 for feeding the carbons or electrodes.

Other objects of the invention will appear hereinafter.

In the accompanying drawings, which illustrate the invention, Figure 1 is a perspective view of a headlight with the door of the casing open showing the interior mechanism within the casing. Fig. 2 is a central longitudinal section of the headlight. Fig. 3 is a side elevation of the headlight 75 showing the manner of removal of the interior mechanism from the casing. Fig. 3^a is a detail view. Fig. 4 is a perspective view of the interior mechanism, enlarged.

Referring to the drawings, the headlight 80 comprises a casing 1, having a rear end wall 2, while at its front end is hinged a door comprising a frame 3 in which is secured a glass 4. To accommodate the interior mechanism without unduly increasing the size of 85 the casing, a raised section 5 is provided at the top of the casing, which section preferably extends but a portion of the distance from the front to the rear of the casing. An upwardly projecting portion 6 upon the 90 door serves to close the front end of the raised section of the casing when the door is closed. The casing may be supported in any suitable manner, the means shown comprising hooks 7 and 8 secured to the back of the 95 casing and adapted to be hung over the edge of the dash of a car or in suitable sockets carried by the dash. Near the bottom of the rear wall of the casing buffers 10, of some resilient material, may be provided to about 100

against the dash when the headlight is supported thereon.

Upon the interior of the casing 1, at the bottom thereof and extending longitudinally of the same, is a support or platform 11 which is fixed to the casing. Extending from the forward end of this support are two fixed lugs 12 and 13 between which extends a rod 14. Extending longitudinally 10 of the casing and along the bottom side thereof is a base 15 for supporting the arc lamp mechanism, this base resting upon the support 11 when the interior mechanism is in position within the casing 1. The front 15 end of the base 15 extends between the lugs 12 and 13 and beneath the rod 14 so that it is securely held against vertical or lateral movement while free to rock about the rod 14. Shoulders 16 and 17 upon the base 15 20 bear against the lugs 12 and 13, the base being thus secured against forward sliding movement with relation to the casing. The forward end of the base is rounded as shown and the lugs 12 and 13 are also rounded so 25 that the base may be turned about the rod 14 as a pivot, as indicated in Fig. 3, when it is desired to remove the interior mechanism from or replace it within the casing 1. When the base 15 rests upon the support 11 30 a stud 18 which is fixed to the support 11, and, therefore, to the casing, extends through a hole 19 in the base 15 and serves to hold the base and its mechanism from sliding rearwardly in the casing. The stud 35 18 is screw threaded and fitted with a thumb nut 20 by which the base is securely clamped to the support 11. The rear end of the base 15 may be adjusted relatively to the platform 11 by means of adjustment screws 15', 40 15^a which extend through the base near its rear end and are arranged to bear against the platform 11. 15^c are lock nuts on the screws 15', 15^a.

Fixed to the base 15 is a support 21 for 45 one of the electrodes 22, usually of carbon, and its regulating mechanism. Rearwardly of the support 21 is a support 23 for the reflector 24 which is concave and preferably parabolic. Rearwardly of the support 23 is 50 another support 25 for the other electrode or carbon 26 of the arc light. In order that the support 21 shall not interfere with the forward projection of reflected rays of light, it is curved out of the path of the rays and 55 is preferably in the form of a ring as shown. For the same purpose the support 23 is curved and is preferably in the form of a ring extending about the rim of the reflector and to which the reflector is secured. The support 25 being at the rear of 60 the light and reflector it is not necessary that this support be curved as indicated in connection with supports 21 and 23.

It will be observed that the arc electrodes are inclined and the arc is formed within 65 the reflector substantially at the focus thereof, this, for well known reasons, producing peculiarly efficient light. At the top of the support 21 is an inclined plate 27 to which is secured an inclined cradle 70 28 for the regulating magnet 29. This cradle serves to protect the regulating magnet and is preferably of iron in order to improve in the well known manner the magnetic circuit of the magnet. To protect the 75 magnet-engaging coil from the heat of the arc, the cradle is preferably lined with asbestos or other suitable heat-resisting material.

Extending from the plate 27 is a guide 80 30 for the upper carbon having an offset 31 to accommodate the clutch ring 32 which surrounds the upper carbon, this carbon passing through holes in the offset as shown, and being supported and guided by the 85 walls thereof. At the end of the guide 30 is arranged suitable means for supporting one end of an arc-inclosing globe 33, the globe and its supports being arranged in the well known manner to produce an arc 90 light, of the type known as "inclosed." The supporting means for the upper end of the globe preferably comprises a collar 33^a, having a reduced portion 33^b, which fits within the globe and holds the latter in proper 95 position, a nut 33^c to prevent the collar from dropping off the guide 30 when the globe is not in position, and a spring interposed between the said collar 33^a and the off-set 31 for maintaining the collar in engagement 100 with the globe. The clutch ring 32 is pivoted to an extension 34 of the plunger or core 35 of the regulating magnet. This extension is preferably rigidly connected to the plunger by a screw thread connection 105 and, in order to bring the end of the extension into more convenient relation to the clutch ring, it deviates laterally from the axis of the plunger, as shown. An adjustable stop for the clutch ring is provided by 110 means of the set screw 36, it serving to regulate the throw of the said ring and consequent length of arc between the electrodes. Through the hole 50 in the reflector projects 115 a lower carbon 26 which is supported by the support 25. The support 25 also serves to support one end of the arc-inclosing globe 33.

The regulating mechanism for the upper carbon will automatically strike the arc and 120 properly maintain the same during the fluctuations due to operating conditions. No such automatic regulating mechanism is necessary for the lower carbon. This lower carbon will, however, gradually burn away 125 and from time to time should be moved

upwardly to compensate for this loss. This movement of the lower carbon is accomplished in the present apparatus by means of a grooved wheel 37, this wheel being 5 adapted to engage with the carbon and having the inside of the groove roughened or knurled to prevent slipping of the wheel upon the carbon when the wheel is turned. This wheel is carried by a shaft 38 which is 10 carried in elongated slots in the lugs 39 and 40 which extend from the support 25. The wheel 37 is pressed against the carbon by means of a spring 41 which engages at its middle in the notch 42 upon the support 25 15 while its ends are bent around pins as 43 upon the sides of the support 25 and bear at their ends against the shaft 38 upon opposite sides of the wheel 37. Any suitable means, as a thumb wheel 38' secured upon 20 the shaft 38, may be provided for turning that shaft. Extending between the supports 21 and 23 are supporting strips 44 and 45 to which are secured receptacles or 25 sockets 46 and 47, which may be of any well known construction, and into which are screwed incandescent lamps 48 and 49, respectively. By causing the upper carbon and its regulating mechanism to communicate with the interior of the reflector 30 through the front and open end of the reflector, the apparatus is greatly simplified and the necessity for forming another hole through the reflector, in addition to the hole for the lower carbon, is obviated; thus 35 the disadvantages attendant upon the presence of this second hole, as heretofore indicated, are avoided.

It will be noted that the regulating magnet is mounted forwardly of the reflector. 40 This permits simplification in the arrangement and construction of the parts. It will further be observed that the axis of the regulating magnet is inclined. This permits gravity to move the plunger or core of the 45 magnet, so that it is not necessary for this plunger to be actuated by other parts of the mechanism or by additional mechanism.

In the operation of the lamp, when no current is flowing the magnet 29 will be 50 deenergized and its plunger will slide downward until stopped by reason of the extension 34 coming against the carbon guide. Under these circumstances the upper carbon will be released from the clutching 55 mechanism and will slide downwardly until it comes in contact with the lower carbon. If now current is turned upon the lamp, the plunger of the regulating magnet will be upwardly attracted and will pull up- 60 wardly one side of the clutch ring 32 and cause the ring to grip the carbon and be carried with it as the plunger moves under the attraction of the magnet. The move-

ment of the carbon will continue until the clutch ring 32 comes against the adjustable 65 stop 36 when the movement of the clutch and carbon will be arrested. The arc will thus be drawn and the carbons will be separated a suitable distance to properly maintain the arc; this distance being adjustable 70 by means of the stop 36. When the clutch ring has come against the stop 36 it is caused to grip the carbon firmly so that there is no liability of the carbon shaking loose from the clutch by reason of the vibration of the car. Upon the cessation of the current or a sufficient decrease thereof, the plunger of the regulating magnet will drop under the action of gravity and release the upper carbon and the latter will approach 75 the lower carbon by a sufficient amount to secure proper conditions, when the regulating magnet will again attract its plunger and the upper carbon will again be elevated. In order to adjust the reflector so 80 as to elevate or direct downwardly relative to the casing 1 the shaft of reflected light rays, all that is necessary is to adjust the screws 15', 15".

What I claim is—

1. In a head-light, the combination of a casing open at one end, a lamp base, a two-part connection between the front end of said lamp base and the open end of said casing constituting means by which the lamp 95 base may be rocked into and out of position within the casing through said open end thereof, and lamp mechanism secured upon said base.

2. In a head-light, the combination of a 100 casing open at one end, a lamp base, a tongue and socket connection between the front end of said lamp base and the open end of said casing constituting means by which the lamp base may be rocked into 105 and out of position within the casing through said open end thereof, and lamp mechanism secured upon said base.

3. The combination of a concave reflector having a single opening thereto arranged at 110 one side of the focal axis of the reflector, inclined arc light carbons having their adjacent ends between the front end and center of said reflector and the lower carbon extending through said opening therein, a 115 support for said reflector, a support for the lower arc light carbon, a regulating mechanism for the upper carbon extending with said upper carbon through the front open end of said reflector, and a support for said 120 regulating mechanism arranged in front of said reflector.

4. The combination of a base, a reflector provided with an opening in its lower portion, a support for the reflector carried by 125 said base and connected to said reflector, in-

clined upper and lower arc light carbons arranged within the reflector, a support for the lower carbon carried by the said base, and arranged rearward of the reflector support, the said lower carbon and its support extending through said opening, a support for the upper carbon carried by the said base and arranged forward of the said reflector support, and regulating means for 10 the upper carbon carried by the upper carbon support and arranged forward of the reflector.

5. The combination of a base, a reflector provided with an opening in its lower portion, a support for the reflector carried by the said base, inclined upper and lower arc light carbons arranged within the reflector, a support for the lower carbon carried by the said base, and arranged rearward of the reflector support, the said lower carbon and its support extending through said opening, a support carried by the said base extending around the reflector and provided with a depending guide for supporting and guiding the upper carbon, and regulating means for 25 the upper carbon mounted on the last mentioned support, the said upper carbon and its regulating means being arranged forward of the reflector.

30. 6. In a lamp of the class described, the combination of upper and lower relatively movable alined carbons, a support for the lower carbon, a stationary U-shaped support having alined guideways through its legs for the upper carbon, an electromagnet having a plunger with its axis parallel to the axis of said carbons, a clutch ring surrounding and engaging said upper carbon between the guideways of said U-shaped support and having a rigid lateral extension, and a member connected at its upper end directly with said plunger and at its lower end having a pivotal connection with the lateral extension of said clutch ring.

45. 7. In a lamp of the class described, the combination of upper and lower relatively movable alined carbons, a support for the lower carbon, a U-shaped support having alined guideways through its legs for the upper carbon, an electromagnet having a plunger with its axis parallel to the axis of said carbons, a clutch ring surrounding and engaging said upper carbon between the guideways of said U-shaped support and having a rigid lateral extension, a member connected at its upper end directly with said plunger and at its lower end having a pivotal connection with the lateral extension of said clutch ring, and means between the legs 55 of said U-shaped support for varying and limiting the distance of movement of said clutch ring between the alined guideways.

60. 8. In a head-light, the combination of a

casing, a base arranged within said casing and having swingable connection therewith arranged between the front end of the casing and the front end of the base, lamp mechanism including a reflector carried by said base, and means for vertically adjusting the rear end of said base relative to 70 said casing.

9. In a device of the class described, the combination of a parabolic reflector having but a single opening therethrough and it arranged beneath the focal axis of the reflector, inclined upper and lower alined arc light carbons, the latter extending through said opening, a support for said lower carbon, a separate support for said upper carbon, regulating mechanism for the upper 80 carbon arranged entirely in front of said reflector and extending into the interior thereof through the front open end of the reflector and above the focal axis thereof, and means for supporting the regulating 85 mechanism.

10. A light mechanism comprising a support provided with a socket at one end, consisting of a pair of lugs and a rod extending from one lug to the other, a base mounted on the support with one end arranged within said socket, means for detachably securing the opposite end of the base to the support, and a light mechanism carried by the said base.

95. 11. A light mechanism comprising a support provided with a socket at one end, consisting of a pair of lugs and a rod extending from one lug to the other, a base mounted on the support, the said base having a reduced end arranged removably within the said socket, means for detachably securing the opposite end of the base to the support, and a light mechanism carried by the said base.

105. 12. A light mechanism comprising a support provided with a socket at one end, consisting of a pair of lugs and a rod extending from one lug to the other, a base mounted on the support, the said base having a reduced end arranged removably within the said socket, and the said socket permitting the opposite end of the base to swing upwardly on a transverse axis, means for detachably securing the base at that end opposite the socket to the support, a light mechanism carried by the said base, and adjusting devices interposed between the base and support for the purposes specified.

115. 13. In a headlight, a bell-shaped reflector, means for supporting said reflector, a ring carried by said means and located in front of the mouth of said reflector, a support carried by said ring and extending into said reflector, an electrode, and operating means 120 therefor carried by said support.

14. In a headlight the combination of a bell-shaped reflector with a bar supported at the front end thereof and projecting inwardly into the reflector, and an electrode mounted on the bar, said bar and electrode being in substantial parallelism with the sides of the cross-section through the reflector.
15. In a headlight a bell-shaped reflector, means for supporting said reflector, holding means located near the mouth of said reflector.

tor, a support carried by said holding means and extending into said reflector and an electrode, and operating means therefor carried by said support.

In testimony that I claim the above, I have hereunto subscribed my name in the presence of two witnesses.

CHARLES J. GETERMAN.
